UNITED STATES PATENT OFFICE.

MARTIN LIEDL, OF BERLIN-STEGLITZ, GERMANY.

ELECTROMOTIVE DRIVE FOR CALCULATING MACHINES.

Application filed December 24, 1921. Serial No. 524,753.

To all whom it may concern:

Be it known that I, MARTIN LIEDL, of German nationality, residing at 25 Ahornstrasse, Berlin-Steglitz, Germany, have invented certain new and useful Improvements in and Relating to Electromotive Drives for Calculating Machines; and I do hereby declare the following to be a full, clear, and exact description of the invention, 10 of which the following is a specification.

The invention relates to that type of electromotive drives for calculating machines, whereby for each calculating operation the electric motor is mechanically coupled with 15 the shaft of the machine. If the machine itself is not used for a longer period, it can happen with this kind of drives that current is wasted in case the attendant omits to cut out the quietly running motor. This negligence on the part of the attendant is frequently followed by a rapid wearing out of the motor and by a fusing of same.

It has therefore already been proposed to construct the driving mechanism in such 20 a manner that the circuit is automatically broken when the machine is not being used.

The characteristic feature of the present solution of the problem known in itself consists in causing the breaking of the current 25 by the electric motor itself in such a manner that after a certain length of time after every actuation of the operating key the armature circuit is broken by a switch element which is excited by the electric current.

Upon the accompanying drawings an electromotive drive of this type has been shewn 30 by way of example, and it is:

Fig. 1 the general arrangement of the switch mechanism,

Fig. 1^a, a partial view of the switch elements in a slightly altered position,

Fig. 2, the view of an intermediate position of the switch mechanism, and

Fig. 3 in full lines the view of said mechanism in the position of rest.

The illustrated switch mechanism acts in the following manner:

If with the object to engage the coupling the draw rod 1 is pulled in the direction of 40 the arrow, the lever 2, which turns on the fixed pin 3, is lifted out of the notch of the catch lever 4, whereby this lever can yield to the right and thus the machine according to known proceedings is coupled with the 45 motor.

Fig. 3 shews in the position indicated by

the full lines the position of rest of the switch mechanism previous to the commencement of the operation.

The slide 6 by virtue of the spring 13 rests 50 below with its notch 10 on the slide pin 12 and above with the snug 7 on the heating element 14.

In this position the two insulated stop pins 15 and 16 keep the contacts 20 and 21 55 opened.

If now the lever 2 (Fig. 1^a) is actuated by the draw rod 1, by means of the roller 5 the slide 6 is first turned about the slide pin 12 until the slide 6 rests against the stop 70 11 (Fig. 1^a, position shewn in full lines). Upon a movement of the stop pin 15 mounted on the slide, the contact 20 is closed and the motor is started as such may be seen from the switch board diagram. 75

When the lever 2 is further deflected, the slide 6 turns about the stop 11 until the bottom notch 10 of the slide 6 leaves the slide pin 12.

Under the action of the spring 13 the slide 80 6 now moves upwards until it strikes against the heating element 14 with its edge 7^a (Fig. 1^a position of parts shewn in dotted lines).

Together with the slide 6 also the stop pin 16 moves and enables a closing of the contact 21 which controls the circuit passing 85 through the heating element.

The current entering through the base plate 17 passes now through the contact lever 19 and contact 21 to the heating winding 23 90 of the heating element 14 and causes the latter to be heated. As it consists of two bars of different metal the coefficients of expansion of which varying very widely from each other, it will upon its becoming heated 95 bend downward with its free and right hand end providing the two metals are arranged in the right position to each other.

Owing to the pressure which the heating element 14 in consequence of this bending 100 exerts on the slide 6, the latter is moved downward until under the action of the tension spring 13 it drops from the sliding surface 8 moving on the slide pin 12 into the notch 10.

The slide 6 when falling into this oblique position and pressing with its bottom catch on the contact lever 19, pulls the contact 21 apart, whereby the current passing through the heating winding 23 is broken. 110

In consequence thereof the heating element 14, no longer affected by heat through

the heating winding 23, commences to gradually cool off and thereby tends to return to its original straightened position from its downward bent shape caused by the 5 heat. This means that in the present instance the heating element moves with its right hand and free end upwards.

Since the slide 6 owing to its being held fast with its bottom notch 10 by the slide 10 pin 12 cannot make a longitudinal movement, the heating element 14 upon cooling off moves along the snug 7 of the slide 6, until the snug 7 loses its support, and the slide 6 under the action of the tension 15 spring 13 drops now with its upper notch 9 on to bars of the heating element. At this moment the slide 6 by means of its upper stop pin 15 and contact lever 18 pulls the contact 20 apart which is followed by an 20 immediate stopping of the motor 22.

The period between the closing of the current or heating respectively and the cooling-off of the heating element 14 and the disconnecting of the motor caused thereby 25 can be varied at will within certain limits by means of regulating devices so that the motor continues to run even if great intervals of time lie between two successive actuations of the machine.

30 As long as the slide 6 has not yet dropped from the slide pin 12 into the notch 10 (Fig. 2), the movements caused by the machine key and draw rod 1 on to the pawl 2 with its roller 5 are without effect on to 35 the slide 6.

If however in Fig. 2 the slide 6 with its sliding surface 8 is already fallen from the slide pin 12 into the notch 10, the roller 5 upon an actuation of the machine key only 40 pushes back the slide and closes the heating current contact 21 for short periods without the motor contact 20 becoming thereby influenced in any way.

I claim as my invention:—

45 1. In an electromotive drive for calculating machines in combination with a machine key and an electric time switch in the circuit of the electric motor for automatically breaking the current after a predetermined 50 period from the last actuation of the machine key, a bimetallic member, a heating coil surrounding said member and adapted to be switched into the circuit by the actuation of the machine key, an automatic 55 switch member to interrupt the heating current and disconnect the motor after the bimetallic member has cooled down, and means in connection with the said automatic switch member, to prevent the cutting out 60 of the motor as long as the machine key is depressed.

2. In an electromotive drive for calculating machines in combination with a machine

key and an electric time switch in the circuit of the electric motor for automatically 65 breaking the circuit after a predetermined period from a last actuation of the machine key, a bimetallic member, a heating coil surrounding said member, an automatic switch member capable of longitudinal and lateral movement relative to the bimetallic member, machine key operated means to move said switch member, and a pair of contact controlling levers pivoted in fixed 70 relation to the said switch member and operable by catches provided on the latter. 75

3. In an electromotive drive for calculating machines in combination with a machine key and an electric time switch in the circuit of the electric motor for automatically 80 breaking the current after a predetermined period from a last actuation of the machine key, a bimetallic member, a heating coil surrounding said member and adapted to be switched into the circuit by 85 the actuation of the machine key, an automatic switch member comprising a spring controlled slide member, a notch on said slide member, a slide pin to co-operate with said notch, a snug on the slide member to 90 engage one end of the bimetallic member, contact-controlling levers in fixed relation to the slide member, and catch pins on the latter adapted to engage said contact actuating levers. 95

4. In an electromotive drive for calculating machines in combination with an electric motor, a machine key to start the motor, a coupling rod operable by the machine key, a pair of contact levers, a bimetallic 100 member and a heating coil surrounding it, a sliding switch member intermediate said coupling rod, the contact levers and the bimetallic member, a pivoted two-arm lever at the end of the coupling rod to move 105 said sliding switch member, a tension spring between the two-arm lever and the said sliding member, means on the sliding member to close the motor and heating circuit when moved into its outermost position, and 110 means also on the sliding member to catch the free end of the bimetallic member and to be repelled by the action of the latter when bending under the influence of heat 115 so as to cause the interruption of the heating circuit and, on the bimetallic member becoming cold, also the interruption of the motor circuit.

In testimony whereof I have signed my name to this specification in the presence 120 of two subscribing witnesses.

MARTIN LIEDL.
